REFRIGERATING APPARATUS

George M. Armstrong, Grand Rapids, Mich., assignor to Nash-Kelvinator Corporation, Detroit, Mich., a corporation of Maryland

Application August 1, 1941, Serial No. 404,996

3 Claims. (Cl. 20—38)

1

The present invention relates to refrigerator cabinets, and more particularly to door construction for such cabinets.

It is an object of the present invention to provide a rigid door construction for refrigerator cabinets having low thermal conductivity.

It is a further object of the present invention to arrange a cross member or brace in a refrigerator door which serves as a securement of the door latch mechanism and for the inner door panel.

It is a still further object of the present invention to provide a cross member which is readily and easily assembled in a door, and which is economical of manufacture.

The invention itself, however, both as to its organization and method of operation, together with additional objects and advantages thereof, will best be understood from the following description of specific embodiments when read in conjunction with the accompanying drawing, in which:

In the drawing:

Fig. 1 is an elevational view of a refrigerator cabinet embodying the present invention;

Fig. 2 is a cross sectional view of the cabinet door taken along line 2—2 of Fig. 1;

Fig. 3 is a fragmentary plan view of the door with the inner panel partially broken away;

Fig. 4 is a fragmentary perspective view showing one end of the cross member and the way it is attached;

Fig. 5 is a fragmentary perspective view showing an opposite end of the cross member and the way it is attached;

Fig. 6 is a fragmentary cross sectional view taken along line 6—6 of Fig. 3; and

Fig. 7 is a fragmentary cross sectional view taken along line 7—7 of Fig. 3.

Shown in the drawing is a refrigerator cabinet 10 having a food storage compartment to which access is had through an opening formed in the front wall of the cabinet and which opening is closed by a door 12. The door is held in closed position by latch mechanism 14 engaging a striker plate 15 secured to the cabinet. A suitable handle 17 is operatively connected to the latch mechanism 14 to unlatch and permit the opening of the door 12.

The door 12 comprises an outer metal panel or shell 20 of dish-like conformation having upwardly extending sides which are flanged inwardly to provide a peripherally extending ledge 22 about the door. The marginal edge portion of the ledge 22 is bent to extend downwardly and

2

then at right angles inwardly to form an L-shape ledge 24 extending peripherally about the door with ledge 22. A frame member 26 is secured, preferably by weld, to the L-shaped ledge 24 extending longitudinally therewith about the door 12 to form a reinforcing frame structure for the panel 20 and the door.

Extending horizontally across the door is a cross member 50 comprising a U-shaped member 52 and a bar extension 54. The bar extension 54 is telescopically arranged with the member 52. One end of the member 52 is formed with a depressed channel portion 56 in central alignment with an upwardly pressed channel portion 57 between which is adapted to slide the bar 54. The end of the bar is hooked to engage the downwardly turned edge 59 of the frame member 26. The opposite end of the U-shaped member 52 is recessed as at 60 in the bight section with notches 62 cut in the leg sections 64. The notches engage the edge 59 of the opposed side of the frame member 26.

The cross member 50 extends between the side walls and is positioned so that the legs 64 embrace opposite sides of the latch mechanism. To assemble the cross member to the door, the legs 64 are moved under the frame member 26 until the edge 59 locks into the notches 62, upon which the cross member is aligned for the outward movement of the bar extension 54 to hook under the edge 59 of the frame structure along the opposite side of the door. The bight section is recessed in a manner to provide opening for the latch mechanism but having its edge 63 over-lap to engage the marginal edge of the frame of the latch mechanism. As the cross member is locked under the frame member 26, it will press the latch casing downwardly against the outer panel. The latch casing is also secured by screws 67 to the frame member 26. By this arrangement there is provided a tight wedging of the latch casing between frame, cross member and outer door panel.

Extending along the edge of the door is a door seal or gasket 70 adapted to engage against the front wall of the cabinet adjacent the opening to the food storage compartment to form a seal against air entering the food storage compartment. The gasket 70 is formed with a tongue or locking section 72 adapted to rest upon the frame 26. The gasket extends over the tongue section to form a pocket into which is receivable the marginal edge of the inner door panel 74. The panel 74 is cushioned upon the tongue 72 and

together are secured by screws 75 to the frame 26.

The inner door panel 74 is preferably formed of compositionally non-heat conducting material, such, for example, as plastics. A characteristic of this type of panel is its tendency to absorb moisture that condenses thereon which causes a swelling and expansion of the panel, and if fixedly secured results in buckling or warping of the panel. To prevent buckling or warping, there is provided an enlarged opening 90 in the center of the panel through which is adapted to pass a screw 92 to thread into the cross member 50. A cover cap 94 is frictionally attached over the head of the screw 92.

Suitable heat insulation 96 is placed between the inner panel and outer shell 20. The insulation is slit for the receiving of the legs 62 of the cross member to prevent sliding movement of the end 54 of the cross member along the frame member. The insulation is also slightly compressed by the cross member to further aid in retaining the ends of the cross member in interlocking relation with the edge of the door frame.

In the present arrangement the cross member serves both to secure the latch mechanism and permit a central securement of the inner panel. Though only a single cross bar is shown in the present invention, it is obvious that any desired number may be used for the further securement of the inner door panel and may be positioned either parallel to the member 50 or extend vertically between the top and bottom walls of the door.

While I have shown and described the preferred form of my invention, I do not wish to limit myself to the precise detail as shown and described, but wish to avail myself of such variations and modifications as may come within the scope of the appended claims.

I claim:

1. A door for a refrigerator cabinet having an

outer metal panel with sides, said sides having an inwardly directed flange portion, a door latch casing supported between said flange and outer panel, a cross member extending between opposite sides of said door in frictional engagement with underside of said flange, and said cross bar embracing the sides and top edge of said casing for wedging said casing against said outer panel.

2. A door for a refrigerator cabinet comprising an outer metal panel and an inner non-heat conducting panel, said outer panel having upwardly extending sides, a flange integral with said sides extending peripherally about said door, a door latch casing supported between said flange and said outer panel, a cross member having one end embracing said casing and extending in frictional engagement with the underside of said flange, the opposite end of said cross member engaging the underside of the flange along the opposite wall of said door, said cross member having a portion engaging the top of said casing for pressing said casing towards said outer panel, and means for securing said inner panel to said cross member.

3. A door for a refrigerator cabinet comprising an outer metal panel and an inner non-heat conducting panel, said outer panel having sides, a flange integral with said sides extending peripherally about said door, a door latch casing supported between said flange and said outer panel, a cross member formed of sections in telescoping arrangement, one end of said cross member embracing said casing and extending in frictional engagement with the underside of said flange, the opposite end of said cross member engaging the underside of the flange along the opposite wall of said door, said cross member having a portion engage the top of said casing for pressing said casing towards said outer panel, and means for securing said inner panel to said cross member.

GEORGE M. ARMSTRONG.
